George D. Richards
ATTORNEY

UNITED STATES PATENT OFFICE

FREDERICK WUESTHOFF, OF MAPLEWOOD, NEW JERSEY

POCKETKNIFE CLIP

Application filed May 7, 1929. Serial No. 361,054.

This invention relates to clips or clamps adapted to be secured to portable articles so as to thereby enable such articles to be readily attached to the pocket of a garment and as readily detached therefrom; and the invention, has reference, more particularly to a novel clip so constructed and arranged as to be easily secured to a pocket-knife so as to enable such pocket-knife to be readily attached to the pocket of a garment and thus carried from place to place.

The invention has for its principal object to provide a novel clip for a pocket-knife that is adapted to be readily and securely attached to the pocket-knife, said clip having a band adapted to extend around a molding strip of the pocket-knife and to be locked thereupon in fixed relation thereto.

Another object of the invention lies in the provision of a novel clip of the above character that is of simple construction, durable and positive in its gripping action.

Other objects of this invention not at this time more particularly enumerated will be clearly understood from the following detailed description of the same.

The invention is clearly illustrated in the accompanying drawings, in which:—

Fig. 1 is a side view of a pocket-knife equipped with the novel clip of this invention;

Fig. 2 is an enlarged edge view of the structure of Fig. 1; and

Fig. 3 is an enlarged sectional view taken along line 3—3 of Fig. 2.

Similar characters of reference are employed in all of the hereinabove described views to indicate corresponding parts.

Referring now to the said drawings, the reference numeral 4 designates a pocket-knife having folding blades 5 and 6 pivoted upon bearing pins 7 and 8 respectively. Folding blades 5 and 6 are suitably tensioned by a bow-spring 9 supported midway of its length upon a bearing pin 10. Bearing pins 7, 8 and 10 extend through aligned apertures provided in the spaced handle-plates 11 and 12 and serve to retain the molding strips 13 and 14 upon the outer sides of the handle-plate.

According to the preferred arrangement,

the novel pocket-knife clip of this invention comprises a suitable resilient clip-bar 15 preferably of metal and having a fixed end and a free end. Clip-bar 15 is positioned exteriorly and centrally of the moulding strip 14 and extends longitudinally along the pocket-knife 4. The free end of clip-bar 15 terminates in a ball-snap 16 which is adapted to snap over and engage the exterior sides of pockets of wearing apparel in the same manner that similar portions of fountain pen clips are adapted to engage the exterior of a wearer's pocket.

The fixed end of clip-bar 15 is preferably formed integral with a clip-band 17 extending transversely upon the exterior of the moulding strip 14. Clip-band 17 is formed with end portions 19 and 20 which extend around the edges of moulding strip 14 and along a suitable recess or channel 18 provided at the inner surface of this moulding strip. The channel 18 is of just sufficient depth to accommodate the end portions 19 and 20 of the clip-band so that the inner surface of moulding strip 14 is flush with the surface 75 of these end portions which combined surfaces are arranged in abutting relation with the outer surface of the handle plate 12. End portions 19 and 20 are formed with terminal locking lugs 21 and 22 respectively 80 which project substantially at right angles to these end portions. Locking lugs 21 and 22 extend into a rectangular aperture 23 provided in the handle plate 12 and engage the side walls of this aperture in locking 85 relation, thereby securely and fixedly retaining the clip-band on the molding strip 14. Any tendency for the clip-bar or clip-band to move transversely of the molding strip 14 is positively prevented by the action of 90 the locking lugs 21 and 22 and these lugs also serve to keep the clip-band tightly drawn about the molding strip, preventing looseness thereof. The sides of channel 18 by engaging the edges of the clip-band also 95 serve to aid the locking lugs in preventing longitudinal movement of the clip-band and clip-bar. The exposed surface of the clip-band may be so shaped as to form a suitable decoration 24 or this surface may be suitably 100

treated to produce an artistic appearance.

In assembling the pocket-knife 4, the novel pocket-knife clip of this invention is readily slipped over an end of the molding strip 14 so as to cause its end portions 19 and 20 to snap into the recess 18, whereupon this molding strip may be placed upon the exterior surface of the handle-plate 12 and the locking lugs 21 and 22 pressed into the aperture 23, thereby locking the pocket-knife clip upon the molding strip 14.

A pocket knife equipped with the novel clip of this invention may be readily slipped into a pocket and carried about in much the same manner as a fountain pen, thereby causing the knife to be always readily accessible, positively retained and conveniently carried.

Owing to the peculiar construction of the novel clip of this invention and the manner of attaching the same to a pocket knife, the clip has been found to be highly durable and positive in its holding action in actual use.

As many changes could be made in the above construction and many apparently widely different embodiments of this invention could be made without departing from the scope thereof, it is intended that all matter contained in the above description or shown in the accompanying drawings, shall be interpreted as illustrative and not in a limiting sense.

What is claimed is:—

1. In combination; a pocket-knife having handle-plates and molding strips secured to the outer surfaces of said handle-plates; and a clip for said pocket-knife, said clip comprising, a clip-band extending around one of said molding strips in gripping relation therewith, and a clip-bar fixed in said clip-band and positioned exteriorly of said molding strip for cooperating with said molding strip to engage a pocket wall of a garment therebetween.

2. In combination; a pocket-knife having handle-plates and molding strips secured to the outer surfaces of said handle-plates; and a clip for said pocket-knife, said clip comprising, a clip-band extending around one of said molding strips in gripping relation therewith, locking means on said clip-band for interlocking said clip-band with one of said handle-plates, and a clip-bar fixed on said clip-band and positioned exteriorly of said molding strip for cooperating with said molding strip to engage a pocket wall of a garment therebetween.

3. In combination; a pocket-knife having an apertured handle-plate and a molding strip secured to the outer surface of said handle-plate; and a clip for said pocket-knife, said clip comprising, a clip-band extending around said molding strip in gripping relation therewith, locking lugs formed

on said clip band and extending into an aperture in said handle-plate for interlocking said clip band with said handle-plate, and a clip-bar fixed on said clip-band and positioned exteriorly of said molding strip for cooperating with said molding strip to engage a pocket wall of a garment therebetween.

4. In combination; a pocket-knife having an apertured handle-plate and a molding strip secured to the outer surface of said handle-plate, said molding strip having a transverse channel at its inner surface; and a clip for said pocket-knife, said clip comprising, a clip-band extending transversely along the exterior surface of said molding strip, and having end portions extending around the edges of said molding strip and into said channel, locking lugs formed on the free ends of said end portions and extending into an aperture in said handle-plate for interlocking said clip-band with said handle-plate, and a clip-bar fixed on said clip-band and positioned exteriorly of said molding strip for cooperating with said molding strip to engage a pocket wall of a garment therebetween.

5. A clip for pocket-knives comprising, a clip-band adapted to extend around a part of a pocket-knife in gripping relation therewith, locking means formed on said clip-band and adapted to engage another part of the pocket-knife for interlocking said clip-band with the pocket-knife, and a clip-bar fixed on said clip band and extending exteriorly and longitudinally of the pocket knife.

In testimony, that I claim the invention set forth above I have hereunto set my hand this 6th day of May, 1929.

FREDERICK WUESTHOFF.
